UNITED STATES PATENT OFFICE.

SAMUEL J. MURRAY, OF INDIANAPOLIS, INDIANA.

PAPER BOX.

SPECIFICATION forming part of Letters Patent No. 434,878, dated August 19, 1890.

Application filed May 6, 1890. Serial No. 350,737. (No model.)

To all whom it may concern:

Be it known that I, SAMUEL J. MURRAY, a citizen of the United States, residing at Indianapolis, in the county of Marion and State 5 of Indiana, have invented certain new and useful Improvements in Paper Boxes, of which the following is a specification.

My invention relates to that class of paper boxes which are intended for repeated use or 10 to serve as cases to repeatedly receive their contents; and it consists in so cutting that portion of the box opposite the tuck that a finger-recess will be formed when the tuck is opened, permitting the convenient withdrawal of the contents with the thumb and 15 finger.

My improved box is specially designed for and peculiarly adapted to contain playing-cards; but it may be used for any other desired purpose.

Referring to the accompanying drawings, which are made a part hereof and on which similar letters of reference indicate similar parts, Figure 1 is a perspective view of a box 20 or case embodying my said invention, illustrating the position of parts when being used and the method of use; Fig. 2, a rear elevation thereof, and Fig. 3 a central vertical sectional view looking toward the left from the 25 dotted line 3 3 in Fig. 2.

In said drawings the portions marked A represent the box or case, and B the contents, which contents are shown as cards.

The box or case A is formed of a size and 30 shape to receive the article which it is intended to inclose. That shown is of the form and construction required to receive a pack of playing-cards. Generally speaking, it is of a character and form which are well known. It is provided with the tuck portion A', which is a continuation of the back side of the box, and is scored or hinged at the top of the box, as usual, and it is cut out at the front edge at the point marked a to permit the thumb 35 of the person removing the contents to come in contact therewith, all as is usual. At the rear side, however, two slits are cut through on lines inside of and parallel with the rear corners, and preferably near the center, leaving a portion a', preferably only a little wider than a human finger, which is adapted to

swing or be forced out into the position shown when the tuck portion is pulled out and swung open and leave a finger-recess, into which the end of the finger of the person desiring to 55 remove the contents may be inserted, so that said contents may be grasped between the thumb and finger, and thus easily removed without the usual danger of tearing or splitting the back of the box or casing. By properly scoring the folds the portion a' naturally 60 opens out, as shown, during the operation of opening the tuck portion; but even if it does not it is easily pushed out by the end of the finger without straining or tearing any other 65 part. It will also be observed that all four corners of the box continue to the extreme edge of the box, thus avoiding the disadvantages which result from cutting said corners down, which disadvantages are in a 70 measure similar to those which result from tearing the corners. The portion between the slits which bulges out comes into place when the tuck is folded and completely covers the contents, the same as though said slits 75 were not present.

Having thus fully described my said invention, what I claim as new, and desire to secure by Letters Patent, is—

1. A box or case provided with a tuck cut 80 or slit through on two lines on its rear side inside of and preferably parallel with the corners, the portion between the cuts being adapted to be swung out when the tuck is opened, and thereby form a finger-recess, substantially as set forth.

2. The combination, in a box or case, of the usual box-body, the flap or tuck portion, and a cut-away portion in front, said flap or tuck portion having two cuts or slits at its rear 90 side inside of the corners, which cuts extend down into the body of the box, whereby the part between said cuts or slits is adapted to bulge out beyond those portions of the back which are alongside it and leave a recess for 95 the finger of the user in withdrawing the contents from the case, substantially as shown and described.

3. A box or case composed of flexible material, having two slits cut through the body 100 of the structure on one side and having a portion of one side bounded by said slits

along its sides, but remaining attached to the structure at its ends, whereby said portion is adapted to be forced or bulged out when the box is open, but which closes up and 5 forms a part of the inclosing structure when the box is closed, substantially as described, and for the purpose specified.

In witness whereof I have hereunto set my hand and seal, at Indianapolis, Indiana, this 2d day of May, A. D. 1890.

SAMUEL J. MURRAY. [L. S.]
